UNITED STATES PATENT OFFICE.

AIME MONTELLS, OF NEW YORK, N. Y.

FLYING MACHINE.

Application filed October 18, 1922. Serial No. 595,272.

To all whom it may concern:

Be it known that I, JAIME MONTELLS, a subject of the King of Spain, residing at New York, in the county of New York and 5 State of New York, have invented certain new and useful Improvements in Flying Machines, of which the following is a specification.

This invention relates generally to flying 10 machines, having particular reference to a flying machine utilizing to partially sustain it in the air.

The invention has for an object to provide a novel flying machine of this type 15 provided with lifting and propelling helices, the invention having for a further object to provide a simple means for effecting a relative control of the said lifting and propelling helices.

20 For further comprehension of the invention, and of the objects and advantages thereof, reference will be had to the following description and accompanying drawings, and to the appended claims in which 25 the various novel features of the invention are more particularly set forth.

Fig. 1 of the drawings is a side view of my improved flying machine.

Fig. 2 is a transverse section on the line 30 2—2 of Fig. 1.

Fig. 3 is a plan view of the control valve, omitting the operating handles.

Fig. 4 is a front elevational view of the valve and its operating mechanism, the 35 valve casing being shown in longitudinal section.

Fig. 5 is a transverse vertical sectional view thereof taken on the line 5—5 of Fig. 4.

In constructing my improved flying machine I provide an elongated gas bag 10 which may be of the non-rigid type, this bag being of just sufficient size to sustain the machine when the latter is fully equipped. Fitted around the lower portion of the bag 45 10 is a horizontal rail 11 which extends completely therearound. To this rail are connected the upper ends of the inclined struts 12 whose lower ends are fastened to an elongated cabin 13 for crew and passengers. Attached at their upper ends to the bag 10 in any suitable manner are pairs of ropes 14 which extend downwardly on opposite sides thereof, the two ropes of each pair being united at their lower ends to a single rope 15 which extends downward and is fastened to the top of the cabin 13.

These ropes act both to suspend the cabin, and also, by holding the rail 11 in tight contact with the gas bag 10, prevent swaying of the cabin.

For raising and lowering my improved flying machine I provide a series of four helical propellers 18 which are supported by brackets 19 on the struts 12. These propellers 18 have fixed thereto turbine wheels 60 20 of usual construction. For driving the machine I provide the fore and aft helical propellers 21 suitably supported by cross braces such as 22 and having fixed thereto turbine wheels 23 of ordinary construction. 65

For driving these propellers I provide a steam boiler 25, preferably heated by oil, and from which steam is delivered to the respective turbine 20 and 23 through two main leads 26, 27 having suitable branches 70 such as 28, 29 leading to the respective turbine wheels, the flow of steam through these leads being controlled by a novel valve device illustrated in Figs. 3, 4 and 5.

As there shown a pair of axially aligned 80 plugs 30, 31 are rotatable in a casing 32 and have ports 33 and 34 leading therethrough. These ports are adapted to both communicate at one end with a manifold chamber 35 suitably connected to the steam 85 boiler 25 and at their opposite ends with the respective pipes 26 and 27. These ports are normally positioned at such an angle with respect to one another that one closes as the other opens, so that the steam supply 90 to the lifting propellers is throttled down when the supply to the driving propellers increases, and vice versa.

These plugs 30, 31 are provided with projecting stems 38 on which are elongated 95 gears 39 engaged by other gears 40 on a telescopic shaft consisting of outer and inner sections 41 and 42, this shaft having a hand lever 43 thereon for purposes of rotation. I also provide means whereby the 100 relative angular positioning of the ports 33, 34 may be varied. As here shown a pin 45 on the outer shaft section 42 engages in a helical groove 46 in the inner section 41. Formed on the two shaft sections are flanges 105 47 between which engages a double ended cam 48 fixed on the upper end of a short vertical shaft 49 on whose lower end is a bevel gear 50 meshing with a like gear 51 on one end of a horizontal shaft 52 on 110 whose opposite end is a worm gear 53 engaged by a worm pinion 54 on the lower

- end of a vertical shaft 55 on whose upper end is a handwheel 56. A tension spring 57 holds the flanges pressing against the cam 48.
- 5 In cases where the exigencies of control require the angular positioning of the ports 33, 34 to be varied the same can be readily done by turning wheel 56, without interfering with the operation by lever 43.
- 10 It will be understood of course that various change and modifications might be made in the precise construction and also that the control valve might be used for other purposes.
- 15 Having thus described my invention what I claim as new and desire to protect by Letters Patent of the United States is as follows:
1. In a flying machine, a gas bag, a cabin suspended therefrom, lifting and driving propellers, turbine wheels fixed to the various propellers, means for directing a fluid under pressure on the turbine wheels, and a valve for controlling the said fluid and adapted to inversely vary the supply of fluid to the two sets of propellers.
2. In a flying machine, a gas bag, a cabin suspended therefrom, lifting and driving propellers, turbine wheels fixed to the various propellers, means for directing a fluid under pressure on the turbine wheels, and a valve for controlling the said fluid and adapted to inversely vary the supply of fluid to the two sets of propellers, said valve comprising a pair of axially aligned plugs having angularly offset ports extending therethrough, and a common operating lever for said plugs.
3. A control valve comprising a casing, a pair of rotary plugs therein, having ports therethrough, means for rotating said plugs in unison, and means for varying their relative angular positioning.
4. A control valve comprising a casing, a pair of aligned rotary plugs therein stems on said plugs, elongated gears on said stems, a telescopic shaft extending parallel to said plugs, gears on the respective sections of the said shaft engaging with the said elongated gears, one of said sections having a helical groove and the other a pin engaging in said groove, and means for moving the respective sections axially on one another.
5. A control valve comprising a casing, a pair of aligned rotary plugs therein stems on said plugs, elongated gears on said stems, a telescopic shaft extending parallel to said plugs, gears on the respective sections of the said shaft engaging with the said elongated gears, one of said sections having a helical groove and the other a pin engaging in said groove, and means for moving the respective sections axially on one another, comprising flanges on the respective sections, a double ended cam engaging between said flanges, and a tension spring connected to the respective sections.

In testimony whereof I have affixed my signature.

JAIME MONTELLS.
